UNITED STATES PATENT OFFICE

JOSEPH A. PHILLIPS, OF BRYANT, INDIANA, ASSIGNOR OF ONE-THIRD
C. M. BRAKE AND D. A. WHITE, OF SAME PLACE.

LIFTING-JACK.

SPECIFICATION forming part of Letters Patent No. 235,289, dated December 7, 1880.
Application filed July 28, 1880. (No model.)

To all whom it may concern:

Be it known that I, JOSEPH A. PHILLIPS, a citizen of the United States, residing at Bryant, in the county of Jay and State of Indiana, have invented certain new and useful Improvements in Lifting-Jacks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improved lifting-jack for use in raising carriage-wheels and partially removing them from the axle when it is necessary to oil them; and the objects of my improvements are to provide a jack the lifting-lever of which is adjustable vertically in a frame, and is provided with a peculiarly-shaped inner end for bearing upon the hub of the wheel in such a manner that as the outer end of said lever is depressed for raising said 25 wheel its inner end will draw the same outward and allow the lubricant to be placed directly upon the arm or axle. I attain these objects by the device illustrated in the accompanying drawings, in which—

30 Figure 1 is a perspective view showing the parts in the positions in which they are placed when the wheel has been raised and partially withdrawn from its axle; and Fig. 2 is an elevation, partly in section, showing the parts as 35 placed beside a wheel for use, and showing, also, a box for the reception of the lubricant and for a wrench or other tools.

Similar letters refer to similar parts in both of the views.

40 In constructing jacks of this character I provide a frame consisting of a base, A, to which are secured two vertical posts, A' and A'', the edges of which are provided with a series of notches or depressions, A³ A'', for the reception of the journals of a lifting-lever, soon to be described.

These posts may be made of wood or iron, or of any other suitable material, and when made of wood they may, if preferred, have a 45 plate of metal attached to their inner or outer

surfaces, which may be provided with notches or depressions corresponding with those the posts over or upon which they are placed for the purpose of preventing the splitting of the projecting portions of said posts.

For the purpose of uniting the upper portions of the posts A' and A'' a bar, A⁴, wood or metal, is extended from one to the other and firmly secured to both, which has the effect to prevent them from being separated. At the proper point, near the lower ends of the posts, there is extended from one to the other another rod, A⁵, which receives and holds in position a dog, B, which is attached to the lifting-lever.

For the purpose of forming a receptacle for the lubricant to be used there is placed upon the base A a box, B', which is provided with a hinged cover, so that it may be readily opened, said box affording a means of keeping always on hand, and where it is always accessible, a supply of lubricating material, and being, also, a receptacle for a wrench or other tools necessary to be used in performing the operation.

For the purpose of raising and partially removing the wheels of various kinds of vehicles there is provided a lever, C, of peculiar construction. The inner end of this lever, or that portion which comes in contact with the wheel in raising it, is to be substantially in the form shown in the drawings, its upper edge being beveled, so as to permit it to bear upon the hub between the spokes of the wheel. This portion of the lever is also rounded upon its upper edge, so that when it is placed in contact with the hub, as shown in Fig. 2 of the drawings, and its outer end is depressed, as shown in Fig. 1, the wheel will be partially withdrawn from its arm or axle. Should it not be withdrawn far enough by this operation all that is required to still further remove it is to take hold of the rod A⁴ and tip the frame outward until the wheel has been removed the required distance, when the lubricant may be applied and the wheel returned to its position on the axle by returning the frame to its vertical position and raising the outer end of lifting-lever C.

For the purpose of making the lifting-lever

etrically adjustable upon the post there is attached to or formed upon it journals C' C², which extend therefrom sufficiently far to allow them to rest in the notches formed upon the posts A' A², and thus, by raising or lowering said lever, it will be accommodated to use in raising and removing wheels of different sizes.

The dog or ratchet-bar B, above alluded to, pivoted to lever C, as shown, its lower end being provided with depressions for engaging with the rod A⁵, so that the lever may be secured in any position within its range of movement.

Having thus described my invention, what I claim, and desire to secure by Letters Patent, is—

The combination of the lifting-lever C, having its inner end rounded, as described, the notched posts A' A², and the dog B, the parts being arranged for joint operation substantially as set forth.

In testimony whereof I affix my signature in presence of two witnesses.

JOSEPH A. PHILLIPS.
